RALPH EDWIN HOUGHTON AND MICHAEL JOSEPH HANLON, OF CLIFTONDALE,
MASSACHUSETTS.

EMERY-WHEEL REST.

1,180,041.

Specification of Letters Patent.

Patented Apr. 18, 1916.

Application filed September 9, 1915. Serial No. 49,717.

To all whom it may concern:

Be it known that we, RALPH E. HOUGHTON, a citizen of the United States, and MICHAEL J. HANLON, a subject of the King of Great Britain, residents of Cliftondale, Saugus, in the county of Essex and State of Massachusetts, have invented a new and Improved Emery-Wheel Rest, of which the following is a full, clear, and exact description.

Our invention relates to emery-wheel rests, and an object thereof is to prevent the jamming of the tool between the rest and the wheel, which causes the breakage of the emery wheel and frequent injury to the workmen.

A further object of the invention is to provide a simple, convenient, strong and easily adjustable rest for emery wheels and whereby working on the wheel is rendered safe.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a plan view of the rest coöperating with an emery wheel; Fig. 2 is an elevation of the rest with one of the tool supports in inoperative position; Fig. 3 is an end elevation of the rest; Fig. 4 is a modified structure of the rest; and Fig. 5 is an end elevation of the rest shown in Fig. 4.

Referring to the drawings, 6 is the base of the rest, preferably U shape, to receive between the branches of the U, that is to say, in the recess, the emery wheel 7. Formed integrally with the base are paired lugs 8 in which are mounted to swing supports 9 and 10, the supports 10 being mounted on the branches of the frame to swing transversely of the recess in the frame, while the support 9 is mounted to swing longitudinally of the recess. The upper end of each support is preferably curved toward the recess to bring the extremities of the supports in close proximity to the emery wheel 7. The extremities of the supports are prevented from engagement with the emery wheel by resting lugs 11 projecting from the support and

engaging the under side of each of the supports 9 and 10. The extremity of each support at the wheel forms a sharp edge. The upper surface of the support adjacent the edge is preferably substantially horizontal, 60 and whereat the tool rests when it is worked upon.

The support 9 forms a rest for a tool when the same is being ground on the periphery of the wheel; while the similar supports 10 form a rest for a tool when it is being ground on the sides of the wheel. The action is the same in all three supports; that is to say, should a tool or any wedge-shaped piece be engaged between the wheel and the support, the latter will immediately swing back, as shown in full lines in Fig. 2 and in dotted lines in Fig. 3, due to the resistance offered instinctively by the worker to the engagement of his tool. This swinging of the support will allow the tool to drop into the water pan where the wheel is mounted.

The base plate 6 is provided with slots 12 for receiving the securing bolts 13, whereby the base plate can be adjusted relatively to 80 the wheel. When the rest is used on wheels having a tapering cross section, the supports 10 are mounted on a swivel adjustment, to dispose the edges thereof parallelly to the ends of the wheel.

In Figs. 4 and 5 a modified structure of the rest is shown. The base 14 can be secured by any suitable means to any type of a grinder frame. The central part 15 of the base is raised through the major part of the base length, and it has a longitudinal recess forming a seat for the cylindrical part 16 of the tool support 17. The cylindrical part 16 of the support has a pin 18 fitting into a groove 19 in the base, whereby longitudinal displacement of the support in its bearing is prevented. The sharp edge of the support 17 is maintained clear of the wheel 20 by the engagement of the projection 15 with the support adjacent the cylindrical part 16 thereof. The swinging movement of the support when the tool is jammed between the support and wheel is similar to what has been described for the supports 9 and 10.

We claim:

1. In a tool rest for grinding wheels, a base, a tool support on the base mounted to swing at its lower end, said support having a portion thereof at the upper end bent lat- 110

- erally for presenting an edge to a grinding wheel, and means on the base for engaging the bent portion of the support whereby said edge is maintained in operative position to one side of the swinging axis of the support, said support being free to swing away from said means to be moved into inoperative position, substantially as and for the purpose set forth.
13. 2. A tool rest for grinding wheels comprising a U-shaped base, pairs of lugs on the branches of the U and on the portion joining the branches, tool supports engaging the pairs of lugs at their lower end, a pivot connecting each of the supports to the lugs whereby said supports are free to swing on the base, each of said supports having a portion thereof at the upper end bent laterally for presenting an edge, and resting lugs on the base for each of the supports for engaging the bent portion thereof and maintaining the edge in a predetermined position over the recess between the branches of the U base, each of said supports being free to swing away from the resting lugs, substantially as and for the purpose set forth.
3. A tool rest for grinding wheels comprising a support mounted to swing to and from a grinding wheel, and a rest for the support for maintaining it spaced from the wheel the relation between the grinding surface of the wheel, the part of the tool support spaced from the wheel and the pivot

of the support being such that when a tool is drawn between the support and the wheel the support is caused to swing on its pivot away from the wheel.

4. A tool rest for grinding wheels comprising a base having lugs, a support mounted to swing in the lugs, said support forming an edge at the free end thereof, and a rest on the base for the support to present the edge of the support in spaced operative relation to a wheel, said edge of support being so formed and so related to its pivot and the surface of the wheel that when a tool is drawn between the wheel and the edge the support is caused to swing on its pivot away from the wheel. 50

5. A tool rest for grinding wheels comprising a tool support mounted to swing at its lower end to and from a grinding wheel, and a rest for maintaining the other end spaced from the grinding surface of the wheel, so that when a tool is drawn between the end and the grinding surface of the wheel the support is caused to swing on its pivot away from the wheel. 55

In testimony whereof we have signed our names to this specification in the presence of two subscribing witnesses.

RALPH EDWIN HOUGHTON.
MICHAEL JOSEPH HANLON.
